FASTENING FOR CONCRETE POURING FORMS

Application filed September 19, 1930. Serial No. 482,951.

This invention relates to devices for fastening in assembled relation forms for molding or shaping concrete structures.

This invention has for its principal object 5 to provide a novel fastening device of the wedge type which may be employed especially with tie-wires, tie-rods and similar elements employed to hold form walls in place; which fastening device may be quickly and easily 10 manipulated to clamp and tightly draw together the form walls so as to lock the same in place.

This invention has for a further object to provide a novel fastening device which is a 15 unit, that is, which is so arranged as to its parts that the same are retained in mutual operative relation both when in use and when removed from the forms.

This invention has for another object to 20 provide a simple and effective fastening means for securing and tightening up wire-ties or other bendable members which are so commonly used for holding the form structures in place, and which, notwithstanding 25 such adaptability, may also be used at will for securing tie-rods or other similar links.

Other objects of this invention, not at this 30 time more particularly enumerated, will be understood from the following detailed description of the same.

This invention is illustrated in the accompanying drawings, in which:—

Fig. 1 is a fragmentary sectional view of a 35 form structure, showing the operative application thereto of the novel fastening device of this invention as arranged to secure and tighten up wire ties for holding the form elements assembled, said fastening device being shown in side elevation; Fig. 2 is a horizontal sectional view, taken on line 2—2 in Fig. 1; Fig. 3 is a transverse vertical section, taken on line 3—3 in Fig. 2; Fig. 4 is a side elevation, showing a slightly modified relation of the wire tie to the fastening device; 45 and Fig. 5 is a horizontal section, taken on line 5—5 in Fig. 4.

Similar characters of reference are employed in the above described views, to indicate corresponding parts.

The use of the novel fastening device of

this invention has been illustrated in the drawings in connection with a common type of concrete wall form, although it will be understood that the same is applicable to many other specific types of forms. The wall 55 form shown comprises, laterally spaced side members 6, usually maintained in desired spaced relation by intermediate stretchers or spacer pieces 7 extending therebetween. Battens 8 abut the outer faces of the side members 6, and wire ties 9 are engaged around the battens and through the form to draw and hold the side members into the proper 60 positions determined by the stretchers or spacer pieces 7.

The novel fastening device of this invention comprises a wedge receiving element or abutment block 10 having a longitudinal or axial opening or chamber 11 therein, and being further provided, adjacent to its outer 70 end, with internally threaded laterally and oppositely projecting bosses 12 in which are respectively engaged set-screws 13. The said set-screws 13 thus have their biting ends 13' entered from opposite sides into the opening or chamber 11, so that the same may be manipulated to grip and hold the end of a tie 75 means therebetween. Integrally formed with and at the inner end of said wedge receiving element or abutment block 10 are lat-

erally and oppositely projecting portions or lugs 14 having forwardly extending wings 15 overhanging the adjacent end of said wedge receiving element or abutment block 10. The end of said wedge receiving element or abutment block 10, between said wings 15, provides an abutment face 16 to engage the inclined face of a wedge member, as will presently appear. Formed at or near the extremities of said wings 15, to project inwardly from the inner sides thereof, are keeper lugs 17 for purposes subsequently herein explained. The outer faces of said wings 15, and projecting portions or lugs 14 from which they spring, are provided with longitudinally, and preferably inwardly inclined, seating grooves or channels 18. Lateral openings 19 are provided in opposite side walls of said wedge receiving element or abutment block 10 100

adjacent to the rearward ends of said seating grooves or channels 18.

The reference character 20 indicates a wedge member which is arranged for longitudinal movement between the wings 15 of said wedge receiving element or abutment block and slidingly against the abutment face 16 of the latter. This wedge member is so formed as to possess a longitudinal slot 21 which registers with the opening or chamber 11 of the receiving element or abutment block, so that the tie so secured and tightened may be extended through the wedge member, where such arrangement is desired. The vertical plane face 22 of the wedge member is disposed to abut the form structure, while the inclined plane face 23 is disposed to abut the face 16 of the receiving element or abutment block. The sides of the wedge member are provided along the vertical plane face 23, top or broadened and along the inclined plane face 23 respectively with laterally projecting flanges 24, 24' and 24''. The lower extremities of the flanges 24 and 24'' are initially spaced apart to provide a gap 25 through which the keeper lugs 17 of the receiving element or abutment block may be passed, when the wedge member is assembled with the latter, after which the extremity of the flange 24'' is bent inwardly to form a closure member 26 for the gap. Said flanges bounding the sides of the wedge member thus provide enclosed spaces into which the keeper lugs 17 extend, whereby the wedge member, while free for vertical movement relative to the receiving element or abutment block when the device is in use, is nevertheless held against separation from said receiving element or abutment block when the device is removed from a form or not in use.

To permit forcible driving of the wedge member in use, by means of hammer or like blows, and in such manner as not to injure or deform the wedge member, the same is provided at its upper or wide end with a striking anvil or boss 27, as shown.

One manner of using the novel fastening device of this invention to secure and tighten tie-wires 9, or similar bendable or flexible tying elements, is shown in Figs. 1 to 3 inclusive of the drawings. By this manner of use, the tie-wire 9 is engaged about a batten 8 at one side of the form, and its end portions extended through the form walls and form interior, to project beyond the opposite side of the form. One such end portion is passed through an opening in the batten engaging said opposite side of the form, and thence through the wedge slot 21 and opening or chamber 11 of the receiving element or abutment block 10, so as to extend between the biting ends 13' of the set-screws 13. Said set-screws 13 are then screwed inwardly to nip and anchor said tie-wire end portion. The other end portion of the tie-wire is there-

upon extended through a seating groove or channel 18, and thence transversely through the openings 19 of the abutment block 10, from one side of the latter to the other, whereupon its terminal portion is helically wound, as at 28, externally around the body of said abutment block 10. In this manner both end portions of the wire-tie 9 are secured to the abutment block, this having been done while the wedge member 20 is in up-drawn or raised position. The wire-tie 9 having been thus secured, the wedge member 20 may thereupon be driven downwardly so as to wedge between the engaged batten and abutment block, thereby drawing taut the tie-wire to pull the form sides home and thereafter hold the same in place.

Another manner of using the novel fastening device with tie-wires 9 or other bendable or flexible tying elements, is shown in Figs. 4 and 5 of the drawings. In this arrangement, the tie-wire 9 is engaged about a batten 8 at one side of the form, and its end portions extended through the form to the opposite side thereof, one on either side of the adjacent batten. One end portion of the tie-wire is passed along one side of the wedge member 20 and thence along a seating groove or channel 18 at one side of the abutment block 10, and thence transversely through the latter by way of the openings 19, and along the seating groove or channel 18 at the opposite side of the abutment block 10 to meet the other end portion of the tie-wire which is passed along the opposite side of the wedge member. The meeting end portions of said tie-wire are then twisted together, as at 29, or otherwise mutually secured against separation. In this manner the tie-wire is secured in engaged relation to the abutment block 10, while the wedge member 20 is in up-drawn or raised position. The wire tie having been so secured, the wedge member is thereupon driven downwardly so as to wedge between the engaged batten and abutment block, thereby drawing taut the tie-wire to pull the form home and thereafter hold the same in place.

The above described ways of using the fastening device, it will be understood, are illustrative of some of many different ways of securing tie-wires or other bendable or flexible tying elements to the abutment block 10.

From the above description it will be obvious that the novel fastening device of this invention is especially adapted for securing and tightening tie-wires and similar kinds of more or less flexible means for drawing form walls into and holding the same in place; the fastening device, however, is not limited for such uses, since it may with advantage be also used in connection with rigid tie-rods or similar types of connectors, in which case the rods may be secured to the

abutment blocks 10 by the gripping engagement of the opposed set screws.

As many changes could be made in the above described construction and many apparently widely different embodiments of this invention could be made without departing from the scope thereof, it is intended that all matter contained in the above description or shown in the accompanying drawings shall be interpreted as illustrative and not in a limiting sense.

I claim:—

1. In fastener means of the kind described, the combination with flexible tie means of a wedge abutment block having means to receive said tie means in coupled engagement therewith, a wedge member movably disposed between said abutment block and parts from which said tie means extends, and cooperating means on said block and wedge member for movably but non-separably relating the same together.

2. In fastener means of the kind described, the combination with flexible tie means of a wedge abutment block, a wedge member slidably related to an end of said block, cooperating means on said block and wedge for movably but non-separably relating the same together, said block having means to provide external supporting seats for said tie means, and said block also having a transverse passage for the insertion of said tie means therethrough in coupled engagement therewith.

3. In fastener means of the kind described, the combination with flexible tie means of a wedge abutment block having means to provide external supporting seats for said tie means, said block also having a transverse passage for the insertion of said tie means therethrough in coupled engagement therewith, and a wedge member movably disposed between said abutment block and parts from which said means extends.

4. A fastener device of the kind described, comprising a wedge abutment block, a wedge member slidably movable over the forward end of said block, said block having at its opposite sides and forwardly projecting from its forward end wings to overlap the sides of said wedge member, said wings having longitudinal tie-wire seating channels in their outer faces, and said block having a transverse opening rearward of said seating channels to engage a tie-wire transversely through the same.

5. A fastener device of the kind described, comprising a wedge abutment block, a wedge member slidably movable over the forward end of said block, said block having at its opposite sides and forwardly projecting from its forward end wings to overlap the sides of said wedge member, said wings having longitudinal tie-wire seating channels in their outer faces, said block having a transverse opening rearward of said seating channels to en-

gage a tie-wire transversely through the same, said block having an axial passage therethrough, said wedge having a slot registerable with said block passage, and opposed set screws transversely entering said block passage respectively from opposite sides thereof.

6. A fastener device of the kind described, comprising a wedge abutment block, a wedge member slidably movable over the forward end of said block, said block having at its opposite sides and forwardly projecting from its forward end wings to overlap the sides of said wedge member, said wings having longitudinal tie-wire seating channels in their outer faces, said block having a transverse opening rearward of said seating channels to engage a tie-wire transversely through the same, and cooperating means on said block wings and wedge member for movably but non-separably relating the same together.

7. A fastener device of the kind described, comprising a wedge abutment block, a wedge member slidably movable over the forward end of said block, said block having at its opposite sides and forwardly projecting from its forward end wings to overlap the sides of said wedge member, said wings having longitudinal tie-wire seating channels in their outer faces, said block having a transverse opening rearward of said seating channels to engage a tie-wire transversely through the same, cooperating means on said block wings and wedge member for movably but non-separably relating the same together, said block having an axial passage therethrough, said wedge having a slot registerable with said block passage, and opposed set-screws transversely entering said block passage respectively from opposite sides thereof.

In testimony, that I claim the invention set forth above I have hereunto set my hand this 15th day of September, 1930.
